UNITED STATES PATENT OFFICE.

CHARLES WEISE, OF BALTIMORE, MARYLAND, ASSIGNOR TO AMERICAN TOBACCO COMPANY, OF NEW YORK, N. Y., A CORPORATION OF NEW JERSEY.

DESIGN FOR A CAN OR CONTAINER.

43,259.

Specification for Design.

Patented Nov. 19, 1912.

Application filed August 1, 1912. Serial No. 712,788. Term of patent 14 years.

To all whom it may concern:

Be it known that I, CHARLES WEISE, a citizen of the United States, residing at Baltimore, State of Maryland, have invented a new, original, and ornamental Design for Cans or Containers, of which the following is a specification, reference being had to the accompanying drawing, forming part thereof.

The figure is a front elevation of a can or container, showing my new design.

I claim—

The ornamental design for a can or container, as shown.

CHARLES WEISE.
